UNITED STATES PATENT OFFICE

153,516

DESIGN FOR A PLANTER LAMP

Donald P. Gifford, Champaign, Ill.

Application September 16, 1947, Serial No. 141,431

Term of patent 3½ years

(Cl. D48—20)

To all whom it may concern:

Be it known that I, Donald P. Gifford, a citizen of the United States of America, residing at Champaign in the county of Champaign and State of Illinois, have invented a new, original, and ornamental Design for a Planter Lamp, of which the following is a specification, reference being had to the accompanying drawing, forming a part thereof.

Referring to the drawing:

Figure 1 is a three-quarter front view in perspective of a planter lamp, showing my new design; and

Figure 2 is a similar rear view in perspective.

I claim:

The ornamental design for a planter lamp, as shown.

DONALD P. GIFFORD.
